REGULATING NOZZLE FOR VAPORIZING BURNERS

Carl Bernhard Holm, Roslags-Nashy, Sweden

Original application January 29, 1938, Serial No. 187,767. Divided and this application October 11, 1941, Serial No. 414,692. In Sweden July 3, 1937

4 Claims. (Cl. 158—120)

This is a division of my earlier application filed January 29, 1938, Ser. No. 187,767, now Patent No. 2,268,591, dated January 6, 1942, and the present invention relates to gasifying burners and in particular to gasifying burners for small furnaces or ovens, such as portable ovens in which liquid fuel is used as a combustible.

The object of my invention is to provide means for regulating the amount of gas passing through the fuel nozzle of the burner and for effectively cleansing the same.

The quantity of fuel passing through such nozzles is usually regulated by means of a conical needle which co-operates with a nozzle opening. This opening is formed so as to provide a flame of maximum size when the needle is wholly removed from the opening.

Known devices of this kind are subject to a number of drawbacks. The needle in a relatively short time becomes coated with a carbonaceous deposit so that subsequently the possibility of regulating the fuel nozzle opening is considerably decreased since the outflowing vapor due to the coating on the needle changes its direction so that incomplete combustion with a sooty flame results. Moreover, with small valve openings, the nozzle acts as an expansion nozzle and the velocity of the vapor is decreased to such extent that the amount of air required for combustion is no longer drawn by suction into the mixing chamber.

In the case of a cooking stove or the like it is desirable that the same operate with a very small flame and that on the other hand the supply of heat necessary for vaporization is maintained. To obtain this minimum value the needle in prior devices has had to be adjusted with very great accuracy and the desired adjustment becomes practically impossible. Even if the burner after operating with a relatively full flame is adjustable to obtain a minimum flame the needle due to the temperature changes set up when decreasing the flame will be displaced relatively to the nozzle opening so that the correct position of the needle is not maintained.

According to the present invention the regulating nozzle includes two or more needles co-operating with a corresponding number of nozzle openings and adapted to open or close said openings in succession on operation of a single control member which is externally accessible.

The regulating nozzle may comprise a plurality of nozzle openings co-operating with a corresponding number of needles, a common

actuating member externally accessible for controlling the position of all of said needles, each needle having a cross-section substantially similar to that of its corresponding nozzle opening and having a sliding fit in said opening to close the same and the needles being disposed relatively to said openings to produce closing and opening of different nozzle openings in succession.

The openings may be of different cross-sectional areas with the co-operating needles formed of corresponding cross-sections.

The invention will be hereinafter more fully described with reference to the accompanying drawing.

15 Fig. 1 is a plan view of an apparatus constructed in accordance with my invention, part of the cover being broken away;

Fig. 2 shows to a larger scale a section of a detail of the fuel valve operating device; and

20 Fig. 3 shows to a larger scale a section of the fuel nozzle device.

Referring first to Fig. 1, reference numeral 10 designates the casing of a portable oven or heating apparatus having an opening 11 on its upper side. 12 is a reservoir for liquid fuel, such as petroleum, said reservoir being supported by the rear wall of the casing by means of a bracket 13. Through an opening normally closed by a cover 14 the reservoir can be filled with petroleum. A pump 15 the piston 16 of which can be recipro-

30 cated from the outside of the casing by means of a handle 17 secured to the piston rod 18 is provided for producing a super-atmospheric air pressure in the petroleum reservoir, said pressure being indicated by a pressure gauge 19. A conduit 20 connects the reservoir 12 with a control valve 21.

35 By means of a conduit 22 the control valve 21 is connected to the lower portion of a vaporizer 23. Fuel gasified in said vaporizer is 40 discharged through a controllable nozzle device 24 opposite which there is arranged a mixing chamber 25 forming part of a burner chamber generally denoted at 26.

45 For the purpose of starting the vaporizer I provide a starting burner cup 27 arranged to receive starting fuel, such as alcohol, from a measuring device 28 which per se forms no part of the present invention through conduits 29 and 30. The measuring device communicates with

50 an alcohol reservoir 31 which is secured to the rear wall of the casing 10 by means of a bracket 32. Through an opening normally closed by a cover 33 having an air inlet passage 33a the reservoir 31 can be filled with alcohol. By means of a conduit 34, a shut-off valve 35 and a con-

duit 36 the measuring device 28 can be brought into communication with the air space of the fuel reservoir 12.

Having now described the general arrangement of different parts of my improved gasifying burner, I will now proceed with a more detailed description of the main object of the invention.

The fuel valve for completely shutting off the gasified fuel flowing through the nozzle device is indicated at 84 in Fig. 3. The stem 85 of the fuel valve is enclosed, at a portion of its length, by a pipe 86 which has an opening 87 for the admission of gasified fuel into the nozzle chamber 88. The outer end of the valve stem 85 is connected by means of a right-handed thread portion 81 to a screw 82 having left-handed threads. The screw 82 is threaded into a nut 83 secured to the front wall 84 of the casing 10. The screw 82 has an elongation 85 in the form of a rectangularly shaped pin which engages a sleeve 86 secured to a turning button 87. Between the front wall 84 and a projection 88 secured to the sleeve 86 there are arranged abutments 89 and 100 to limit the turning movement of the button 87 within a range from the practically suitable minimum flame to the maximum flame. In order to extinguish the flame of the burner, the projection 88 is moved out of the path of the abutment 89 by drawing out the button 87 against the action of a helical spring 101 inserted between the sleeve 86 and a plug 102 secured to the button and the pin 85. Upon turning the button 87 the threaded portion 81 of the stem 85 will be displaced in axial direction in the screw 82, but it will be prevented from turning movements due to the fact that the threaded portions 81 and 82 are provided with right- and left-handed threads, respectively.

The nozzle device is provided with two openings 105 and 106 of which in the embodiment shown the first-named 105 has a larger diameter than the other one. The valve stem 85 has an elongation 107 carrying a head 108 which has secured thereto two cylindrical needles 109 and 110, of which the one 109 has substantially the same diameter as the larger opening 105, while the needle 110 has substantially the same diameter as the smaller opening 106.

When the valve stem 85 is retracted, the smaller opening 106 is first made free, while the larger opening is still closed. Upon continued retraction of the valve stem, the larger opening 105 is also made free. Since the needles 109 and 110 have substantially the same diameters as the respective nozzle openings, an effective cleansing from coked fuel is obtained, which is not the case in arrangements where the cleansing needle is conical and serves to regulate the size of the flame.

Having now particularly described and ascertained the nature of my said invention and in what manner the same is to be performed, I declare that what I claim is:

1. A gasifying burner comprising, a fuel nozzle device, a fuel valve for shutting off the gasified fuel, said nozzle device having a plurality of openings of different cross-sectional areas, and means connected to said fuel valve for closing or opening in succession any desired number of said nozzle openings.

2. A gasifying burner comprising, a fuel nozzle device, a fuel valve for shutting off the gasified fuel, said nozzle device having two openings of different diameters, and two cleansing needles connected to said valve and having different lengths and being arranged to open or close said nozzle openings in succession upon movement of the valve.

3. A gasifying burner comprising, a fuel nozzle device, a fuel valve for shutting off the gasified fuel, said nozzle device having two openings of different diameters, and two cleansing needles connected to said valve and having different lengths and being arranged to open or close said nozzle openings in succession upon movement of the valves, said cleansing needles being cylindrically shaped and having substantially the same diameters as the respective nozzle openings.

4. A gasifying burner comprising a fuel nozzle device, a fuel valve for shutting off gasified fuel, a stem connected with said valve, means connected with said stem for moving said valve axially, said nozzle having a plurality of openings, and means connected with said valve for successively opening or closing said openings.

CARL BERNHARD HOLM.
